UNITED STATES PATENT OFFICE

143,591

DESIGN FOR A BROOCH OR SIMILAR ARTICLE

Otto Grun, New York, N. Y.

Application December 11, 1944, Serial No. 116,839

Term of patent 14 years

(Cl. D45—19)

To all whom it may concern:

Be it known that I, Otto Grun, a citizen of the United States, residing in the Borough of Manhattan, city, county, and State of New York, have invented a new and original and ornamental Design for a Brooch or Similar Article, of which the following is a specification, reference being had to the accompanying drawing, forming part thereof.

On the drawing,

Fig. 1 is a front elevational view of a brooch embodying my design;

Fig. 2 is a side elevational view of the brooch; and

Fig. 3 is a rear elevational view thereof.

The dominant portion of my design resides in the portion shown in full lines.

I claim:

The ornamental design for a brooch or similar article, as shown and described.

OTTO GRUN.
